CLAIM

The ornamental design for a needle-bearing medical device, as shown and described.

DESCRIPTION

FIG. 1 is a front perspective view of a needle-bearing medical device showing our new design;

FIG. 2 is a left-side view of the needle-bearing medical device shown in FIG. 1;

FIG. 3 is a right-side view of the needle-bearing medical device shown in FIG. 1;

FIG. 4 is a front elevational view of the needle-bearing medical device shown in FIG. 1, with the back view being substantially a mirror of the front view;

FIG. 5 is a top plan view of the needle-bearing medical device shown in FIG. 1; and,

FIG. 6 is a bottom plan view of the needle-bearing medical device shown in FIG. 1.
